UNITED STATES PATENT OFFICE.

HERBERT S. RAUH, OF NEW YORK, N. Y.

CLOSURE FOR UNITING EDGED BODIES.

Application filed August 6, 1927. Serial No. 211,038.

My invention relates to articles intended to function as coverings and which are required to fit more or less closely and to be drawn into place and which, because of the relative 5 dimensions of the element to be covered, require an entrance opening large enough to accommodate said element and permit the article to be easily brought to its intended position. Examples of the article are found 10 more particularly in articles of footwear commonly referred to as leggings, in blouses, in covers for inanimate elements, and the like. In its application to articles of apparel, the invention is concerned more particularly with the means employed to secure 15 a facile mode of application of the article to the person of the wearer.

The object of the invention is to provide an article of the type which is so designed 20 as to fit more or less closely and therefore calls for an entrance opening large enough to admit of its application over the portion of the human body or the inanimate element desired to be covered, with a closure means 25 which will permit the temporary enlargement of at least one end of the article sufficiently to permit its adjustment into the covering position. The invention obviously is applicable to any device which should afford 30 a larger opening when the article is open and being applied than when it is closed and in position.

A more particular object of my invention is to make possible the easy application to, 35 or removal from, the body of articles of apparel equipped with side fastenings of the interlocking type. Such interlocking fasteners have as their main elements, a slider and two serrated strips each attached to its own 40 strip of fabric, these latter being necessarily united at one end to prevent the slider from becoming disconnected from the metallic hooks forming the serrated edges. The invention consists in the particular arrangement and construction in which at least one 45 of the said strips of fabric upon which the serrated columns of interlocking fastenings are mounted is disconnected throughout a portion of its length from the edge of the 50 article, thus permitting a larger opening at said disconnected end. This arrangement necessitates a means of fastening the two upper edges together after the article has been applied and is in its proper position upon the person. This fastening means will

be more particularly described hereinafter. In the accompanying drawings which show several examples of the invention without defining its limits, Fig. 1 is a side elevation of a legging embodying the present invention and shown in the closed or adjusted position as it appears when applied to the leg. Fig. 2 is a side elevation of the legging in the open position or that just prior to and ready for application to the leg of the 60 wearer. Figs. 3 and 4 illustrate the invention as applied to a blouse showing the closure means in the closed and the open positions respectively.

Figs. 1 and 2 illustrate my invention as 70 applied to a legging 1 having the usual meeting edges 2 the closure of which is effected by a slide fastening device 3, consisting of the usual serrated edges 4 and slider 5 of any of the known types now on the market, 75 and the strap 6 of the usual type and design. The legging is provided with a flat strap 7 having a snap fastener member 8 arranged to engage the cooperating member 9 applied in the usual manner to the body of the legging 80 for securing the grip member 10 of the slider 5 when the latter has performed its function in effecting the engagement of the serrated edges. One of these edges is mounted upon a strip of fabric 11 sewn to one of the meeting edges of the legging throughout its 85 length, while the other edge is mounted on another similar strip 11^a secured to the other meeting edge throughout only a portion of its length; the strips 11 and 11^a are permanently united to each other at their upper 90 ends in any convenient manner as for example, by a common tab 11^b offset from the body 1; the latter strip 11^a is disconnected from the corresponding edge of the legging 95 for a suitable distance from the upper end thereof so that when the interlocking slide fastener is in open position the disconnected section of the strip 11^a permits the top portion of the legging to be easily spread apart 100 to a position presenting an opening large enough to admit the foot. The invention obviously may be applied to the bottom of the legging as well as to the top thereof, or only at the bottom of said legging. When 105 the legging is in use the strap 7, slide, and fasteners are in the position shown in Fig. 1, fastening straps 12 engaging with corresponding buckles 13, completing the closure of the legging about the leg and presenting 110

a pleasing appearance as well as providing a snug fit.

The application of the invention to a blouse is illustrated in Figs. 3 and 4 in which 5 the blouse 14 having meeting longitudinal edges 15 is equipped with the usual slide fastening device comprising serrated edges 16 and slide 17 mounted, as in the case of the legging, upon strips of fabric 18. This 10 fabric is disconnected from a portion of the edge of the blouse in the manner and for the purpose above described. The waistband 19 of the blouse is provided at one end with buttons 20 and at the other with buttonholes 15 21 so that the buttoning of the band in the usual manner effects a convenient and presentable means of securing the gripping piece 20 of the slider 17 in position when the blouse is being worn. The tie 22 provides a convenient means of fastening the top edge portions 25 of the blouse together, serving a purpose similar to that of the straps 11 in Fig. 1.

I claim:

1. In combination a body having meeting 25 longitudinal edges, strips of a flexible material attached to said edges and provided with cooperating columns of interlocking fastenings, at least one of such strips being permanently attached to one longitudinal 30 edge for only a portion of its length and being permanently detached from such edge portion for the remainder of its length at one of its ends, a slider for causing interlocking of said columns of fastenings, and 35 means adapted to draw said detached por-

tion and its adjacent body portion toward each other.

2. In combination a body having meeting longitudinal edges, strips of flexible material attached to said edges and provided 40 with a plurality of cooperating fastening elements, said strips being permanently united to each other at one of their ends, at least one of said strips being detached from one longitudinal edge of the body for only a 45 portion of its length at its permanently united end, means for effecting engagement and disengagement of the cooperating fastening elements, and means for drawing together said detached strip portion and said 50 longitudinal edge.

3. In combination an open flexible body having meeting longitudinal edges, strips of flexible material attached to said edges, said strips being permanently united to each 55 other at one of their ends, cooperating columns of interlocking fasteners attached to said strips, a slider for causing engagement and disengagement of said fasteners, the strips thus being separable at all other points 60 throughout their length, at least one of said strips being detached from said body for a portion of its length at its permanently united end to permit enlargement of the body opening, and means for drawing the detached strip portion and its adjacent body portion toward each other to reduce the body 65 opening.

HERBERT S. RAUH.
